ELECTROLYTIC PREPARATION OF A DIHYDRO-STREPTOMYCIN SULPHATE

Morris A. Dolliver, Stelton, and Serge Semenoff, New Brunswick, N. J., assignors, by mesne assignments, to Olin Mathieson Chemical Corporation, a corporation of Virginia

No Drawing. Application December 9, 1949,
Serial No. 132,219

1 Claim. (CL. 204—75)

This invention is concerned with the production of dihydrostreptomycins. These compounds have been obtained heretofore by treatment of the corresponding streptomycins with hydrogen in the presence of a noble metal catalyst, a relatively expensive process in that it necessitates recovery of the catalyst and replacement of catalyst inevitably lost in the recovery. [The terms "streptomycins" and "a streptomycin" employed herein have reference to the recognized genus composed of "streptomycin," "mannosidostreptomycin" and "streptomycin complex"; and the terms "dihydrostreptomycins" and "a dihydrostreptomycin" have reference to the corresponding genus composed of dihydro derivatives of streptomycin, etc. Also, all of these quoted terms, when employed unmodified hereinafter, have reference to these in their usual free-base and/or water-soluble acid-addition forms.]

It has been found that dihydrostreptomycins may advantageously be produced by "electrolytic reduction," i. e., by a process essentially comprising charging an electrolytic cell, having anode and cathode compartments separated by a semi-permeable diaphragm, with a non-alkaline, electric-current-conducting aqueous solution of the corresponding streptomycin as the catholyte and an aqueous acid as the anolyte, passing an electric current between the anode and cathode in the respective compartments until the streptomycin is substantially completely reduced, and recovering the dihydrostreptomycin from the catholyte.

Inasmuch as the process of this invention may be carried out in electrolytic-reduction apparatus generally (i. e., does not require any special type), detailed description and drawing of such apparatus is unnecessary. A simple electrolytic-reduction cell for laboratory use is described, for example, on pages 10-12 of *Organic Syntheses*, vol. 21 published in 1941 by John Wiley & Sons, Inc., New York; it consists of a glass beaker containing a smaller volume porous cup, a mechanical stirrer outside the porous cup, and sheet lead electrodes (one being within the porous cup), the electrodes being in a direct-current circuit having an ammeter and variable resistance, and the beaker being in a cooling bath. The catholyte is placed in the cathode chamber between the permeable diaphragm provided by the porous cup and the beaker wall, and the anolyte within the porous cup, and reduction is effected while stirring and cooling until substantially complete, as evidenced for example by the increased evolution of hydrogen.

The "semi-permeable diaphragm" of electrolytic-reduction apparatus is a diaphragm which permits hydrogen ions to pass from the anode compartment into the cathode compartment and permits the passage of anions (e. g., sulfate or chloride) from the cathode compartment to the anode compartment, but is sufficiently impermeable to prevent diffusion of the catholyte component to be reduced into the anode compartment. Various materials are suitable for use as semi-permeable diaphragms for electrolytic reduction, and may be so used

2

for the purposes of this invention, inter alia, unglazed porcelain, thin cork-pine wood, filtros, and notably Alundum.

The electrodes for the purposes of this invention may be of any of the materials commonly used for electrolytic reduction, provided that the cathode is of a material non-reactive with the streptomycins and dihydrostreptomycins. Thus, the anode may be of lead, lead coated with lead dioxide, platinum, carbon, graphite, tin, zinc, copper, nickel, mercury, amalgamated zinc, and amalgamated lead, inter alia; and the cathode may be of carbon, lead, amalgamated lead, mercury, a noble metal (e. g., platinum), and lead alloyed with other metals (e. g., a solder containing 40% tin, or lead containing about 1-15% antimony), inter alia. Preferably, the cathode is metallic, notably essentially lead. Preferably also, the electrodes (especially the cathode) are in extended surface form, e. g., in the form of coils or sheets, or spongy; and the anode and cathode have substantially the same surface area.

The anolyte for the purposes of this invention may be of any of the compositions commonly used for electrolytic reduction, e. g., aqueous solutions of various concentrations of strong inorganic acids, such as sulfuric, hydrochloric, or phosphoric acid. When electric current is passed through the cell, sulfate ions (for example) are discharged at the anode, reacting with the water to form oxygen and sulfuric acid. Preferably, the anolyte is sulfuric acid in a concentration of about 0.5% to about 80%, notably a concentration of about 33%.

The catholyte for the purposes of this invention is a non-alkaline, electric-current-conducting aqueous solution of the corresponding streptomycin, i. e., a solution in which the streptomycin exists at least in part in the form of its water-soluble acid-addition salt, or a solution in which there is present in addition to streptomycin sufficient water-soluble acid to make the solution non-alkaline and electric-current-conducting. Preferably, the catholyte is an aqueous solution of the hydrochloride or sulfate of the streptomycin. When electric current is passed through the cell, hydrogen ions migrate to the cathode and are discharged as nascent hydrogen, which reacts with the streptomycin in the catholyte to form the corresponding dihydrostreptomycin. Inasmuch as the catholyte tends to become alkaline during the electrolysis, dilute acid is added during electrolysis to maintain the catholyte nonalkaline, preferably at a pH of about 4 to about 7.

The direct current employed may be at various voltages (e. g., 6 volts or 110 volts), the desired amperage being obtained by suitable resistances. Electrolysis may be effected at various amperages (e. g., 0.5 ampere and 15 amperes), and at various temperatures below that at which the streptomycin decomposes in the catholyte (e. g., between about 20° C. and about 40° C.). The higher amperages require more efficient cooling of the electrolytic-reduction cell. The temperature, voltage, amperage and current density are not critical factors in the process of this invention.

By the process of this invention, dihydrostreptomycin, dihydromannosidostreptomycin, and dihydrostreptomycin complex may be efficiently produced from the corresponding streptomycins (streptomycin or streptomycin A, mannosidostreptomycin or streptomycin B, and streptomycin complex, respectively). The concentration of the streptomycin in the catholyte is not critical, concentrations of streptomycin sulfate of about 10% and about 30%, for example, being feasible.

The process of this invention is particularly advantageous in that it permits conversion of the chloride to the sulfate at the same time as the streptomycin is reduced. Thus, using a streptomycin chloride in the catholyte and adding

sulfuric acid to the catholyte during electrolysis, one obtains the corresponding dihydrostreptomycin sulfate substantially free from the corresponding hydrochloride salt and yielding only a faint test for chloride. Inasmuch as crystalline streptomycins are most conveniently obtained as the chlorides, and the dihydrostreptomycins are more desirable physiologically in the form of their sulfates, the process of this invention may be regarded as an advantageous process of converting the streptomycin chloride to the desirable sulfate of the dihydro derivative. By employing the desired acid as the acid added to the catholyte during electrolysis, any desired-acid salt of the streptomycin may be obtained by the process of this invention.

The dihydrostreptomycin formed may be conveniently recovered as its acid-addition salt by removing the catholyte from the cell and freeze-drying the solution; and when the streptomycin employed is of therapeutically-utilizable purity, the dihydrostreptomycin obtained is suitable for therapeutic use without further purification. Further purification of a dihydrostreptomycin obtained by the process of this invention may be effected in the same manner as the purification of a similarly impure dihydrostreptomycin obtained by catalytic hydrogenation.

The process of this invention may of course be carried out in apparatus designed for large scale operation. Thus, the apparatus may include a separate cooling chamber and/or a pH and concentration-adjusting chamber for the catholyte, and means for circulating the catholyte from the cathode chamber to said chamber or chambers and back; and one may employ a number of electrolytic-reduction cells in series, these and other expedients for large scale production being conventional.

The following examples are illustrative of the invention:

Example 1

The electrolytic reduction is carried out in a cell divided into anode and cathode compartments by means of a porous alundum diaphragm, with lead electrodes made of strips of sheet lead containing about 2% antimony, the cathode being helical in shape. The cathode compartment is charged with a 25% aqueous solution of substantially pure streptomycin hydrochloride (810 units/mg.) as the catholyte, and the anode compartment with 0.5% aqueous sulfuric acid as the anolyte. Direct current from a 6-volt D. C. source is applied to the cell at a current density of 2 amperes/sq. cm., while maintaining the catholyte at pH 7 by dropwise addition of dilute sulfuric acid thereto and the temperature at about 20 to 30° C. by cooling. Reduction to the extent of 99.75% is obtained in six hours. The catholyte is then freeze-dried, yielding dihydrostreptomycin sulfate having a potency of about 756 units/mg. in a yield of about 74%. The product gives only a faint test for chloride ion on treatment with silver nitrate.

Example 2

When using 33% (instead of 0.5%) aqueous sulfuric acid as the anolyte in Example 1, and reducing for 12 hours at a current density of 3 amperes/sq. cm., dihydrostreptomycin sulfate having a potency of about 801 units/mg. is obtained in about 94% yield.

Example 3

When using carbon (instead of lead) electrodes in Example 1, and reducing for 15 hours at a current density of .03 ampere/sq. cm., reduction to the extent of about 58% is obtained.

Example 4

When using platinum (instead of lead) electrodes in Example 1, reduction to the extent of about 72% is obtained in 4 hours at a current density of .01 ampere/sq. cm.

Example 5

Under the same conditions as in Example 1 except that

dilute hydrochloric acid (instead of sulfuric acid) is added to the catholyte to maintain it at pH 7, dihydrostreptomycin hydrochloride of comparable potency is obtained in substantially the same yield.

Example 6

Under the same conditions as in Example 1, but with a 25% aqueous solution of substantially pure dihydrostreptomycin hydrochloride as the catholyte, substantially pure dihydrostreptomycin sulfate giving only a faint test for chloride ion is obtained.

Example 7

Under the same conditions as in Example 1, but with a 25% aqueous solution of substantially pure mannosidostreptomycin hydrochloride as the catholyte, substantially pure dihydromannosidostreptomycin sulfate is obtained in high yield.

Example 8

(a) A primary streptomycin-containing liquid (obtained, for example, by culturing *Streptomyces griseus* to produce streptomycin, acidifying the culture, separating the solids from the culture liquid, and neutralizing the separated liquid—as described in Rake, Koerber, and Donovick Patent 2,461,922, dated February 15, 1949) is treated with activated charcoal; and the streptomycin is eluted from the charcoal with dilute hydrochloric acid at about 70° C.

(b) The streptomycin-hydrochloride-containing eluate thus obtained, having a potency of 340 units/ml., is adjusted to pH 6.5 with 2% sodium hydroxide solution, and electrolytically reduced as described in Example 1, adding hydrochloric acid (instead of sulfuric acid) to the catholyte to maintain pH 7, until reduction is complete; and the reduced catholyte is collected.

(c) 10 liters of reduced catholyte obtained as described in (b) is mixed with 36 ml. of a 25% aqueous solution of

[e. g., Tergitol Penetrant 71; and the precipitate formed (a salt-type combination of the dihydrostreptomycin and the surface-active agent) is filtered off and dried. The salt-type combination is then dissolved in 100 ml. methanol, and the impurities filtered off; the filtrate is diluted with 300 ml. water; 60 g. of a neutral anion-exchange resin [e. g., Amberlite IR-4B; cf. U. S. Patent 2,402,384, dated June 18, 1946] is added; the mixture is heated to 50° C.; and concentrated hydrochloric acid is added over a period of a half hour at such rate as to maintain the pH between 3.0 and 3.5. The pH is then allowed to rise to 5.0–5.5, and the resin filtered off and washed with water. The combined filtrate and wash is then vacuum-distilled to remove the methanol, and the residual solution in freeze-dried, yielding 4.6 g. of the hydrochloride of the dihydrostreptomycin, having a potency of 615 units/mg. (yield from eluate, 83.5%).]

The invention may be variously otherwise embodied within the scope of the appended claim.

We claim:

The process of converting a streptomycin hydrochloride into a dihydrostreptomycin sulfate, which essentially comprises charging an electrolytic cell, having anode and cathode compartments separated by a semi-permeable diaphragm, with a nonalkaline, electric current-conducting aqueous solution of said streptomycin hydrochloride as the catholyte and an aqueous solution of a strong inorganic acid as the anolyte, the acid being substantially non-reactive with the anode, and the cathode being substantially non-reactive with the components of the catholyte, passing an electric current between the anode and the cathode in the respective compartments while adding sulfuric acid to the catholyte until said hydrochloride salt is substantially completely converted to a sulfate salt, the electrolysis being effected at a temper-

ature below that at which the streptomycin and the dihydrostreptomycin decomposes in the catholyte and until the catholyte is substantially free of chloride ions, and recovering the sulfate salt substantially free of the hydrochloride salt from the catholyte.
